WAX PAPER FOLDING MACHINE

Frank M. Hitner, Detroit, Mich.

Application March 28, 1938, Serial No. 198,575

11 Claims.

(Cl. 93—84)

This application relates to the art of folding wax paper or the like and discloses methods and machines for continuously unrolling flat wide ribbons of waxed paper from supply rolls on which such ribbons are wound and continuously folding and creasing the unrolled wide ribbons into folded and creased narrow ribbons of the wax paper.

This application is a continuation in part of my prior application Serial No. 119,968 of January 11, 1937.

For an understanding of the methods and machines herein disclosed, reference should be had to the accompanying drawings illustrating the machines. In these drawings,

Fig. 1 is a perspective elevation view of important operating parts of a single folding machine, showing wax paper being folded by such machine;

Fig. 2 is similar to Fig. 1, showing the parts in true elevation;

Figs. 3 and 4 are cross sections on lines 3—3 and 4—4 of Fig. 2;

Figs. 5 and 6 are views similar to but reversed from Figs. 1 and 2, respectively;

Figs. 7 and 8 are, respectively a perspective plan and a true plan of the machine;

Figs. 9 and 10 are cross sections on lines 9—9 and 10—10 of Fig. 8;

Fig. 11 shows a double folding machine;

Figs. 12 and 16 are sections on corresponding lines of Fig. 11;

Fig. 13 is a view as if on the left end of Fig. 11, looking towards the right.

Figs. 14 and 15 are elevation and plan views.

For an understanding of the machine and method of Figs. 1—10 hereof, reference should be had to these figures of the drawings. In these drawings there is shown at 10 a supply

roll of flat wide ribbon of waxed paper WP resting upon a table 11 suitably supported on the frame 12 and adapted to be caused to rotate continuously on the vertical axis of the shaft 14 as indicated. The supporting means for the

roll 10 is made vertically adjustable by suitable means to insure the roll being suitably centered with respect to the remainder of the machine, and particularly the form to be described. Adjacent the table, which comprises a means for

holding the supply roll as it is being unwound, is disposed a vertically mounted guiding roll 15 adjacent which is the head end 16 of a form

17 over which the wide ribbon of waxed paper passes on its way from the vertically mounted

supply roll 10 to the horizontally mounted creas-

ing means. The latter comprises rolls 18 disposed adjacent the tail end 19 of the form 17 and having between them a horizontal slot 20 through which passes the folded ribbon of wax paper as it leaves the form 17. The folded and creased paper passes out of the folding machine in the form of a folded and creased narrow ribbon to the machine which receives the folded ribbon from the folding machine, the receiving machine being either a rewinding machine for rewinding the folded ribbon for storage or a rewinding machine which rewinds and cuts off the folded ribbon into small rolls of suitable length.

The form itself comprises a convex surfaced metal shell S of progressively varying cross section (see Figs. 10, 9, 4, and 3 in order) on whose outer or convex surface is a coating F of loose-woven felt or the like. The provision of the felt coating is of extreme importance and is a very important feature of the invention. The felt prevents slipping of the wax paper ribbon as it rides over the form away from the intended path to be followed by the ribbon and insures the fold being produced in the ribbon at the intended place. Furthermore, the felt coating prevents sticking of the wax paper to the metal shell which would otherwise occur due to static created by the passing of the wax paper over the metal shell. It is understood that other materials than felt might be employed for the same purpose. For example, the coating might be in the nature of cloth, canvas, soft rubber sheeting, loose-woven fiber sheeting, or the like, the important characteristic being that the coating have a rough yielding friction surface of such a nature that the wax paper in passing over the coating will not slip with respect to the coating and at the same time will not stick to the coating due to static.

It will also be observed that in the machine shown the supply roll 10 is vertically mounted whereas the mouth of the slot between the creasing rolls is horizontally disposed. It has been found in actual practice that this relative arrangement, and the disposition of the supply roll on a vertical axis, operates satisfactorily, whereas other arrangements proposed have been found not to operate satisfactorily. It is not now known why the provision of the supply roll on a vertical axis, coupled with the disposition of the creasing slot on a horizontal axis, operates satisfactorily, but it has been found as a fact that it does. It is therefore believed that this is an important feature of the invention.

Resiliently mounted adjacent the tail end 19

of the form and arranged to ride continuously on and against and preferably near an edge of the wax paper as it passes over the form is a rubber-faced squeeze roll 21 which has been found 5 useful to help hold the wax paper against crawling as the paper passes along the form and through the creasing rolls. The provision of the resiliently mounted soft-faced roll riding continuously on the wax paper ribbon as it passes 10 over the form is also considered an important feature of the invention.

In the machine of Figs 11-16, which is a double folding machine, the paper 40 unrolled from the supply roll 41 passes under a thin forming plate 15 42 supported from above by a hanger 43 and the paper then proceeds over the first roll 44 of a rewinder (not shown). On its way from the supply roll 41 to the former 42 the paper passes under a deflecting roll 45 which deflects the paper 20 per so that it assumes the U cross section shown in Fig. 16. As the paper leaves the deflecting roll on its travel along the forming plate 42 it passes under weighted soft-faced rolls 46 which function to fold the paper down onto the forming 25 plate 42 so that as the paper passes beyond the rolls 46 it has the cross section shown in Fig. 12.

As the paper passes over the roll 44 a slitting wheel 47 slits the paper longitudinally as shown in Fig. 13 so that the wide band which left the 30 roll 41 and was folded as it left rolls 46 becomes two independent and separate folded strips to be rewound in the rewinder.

Now having described the machine and method hereof, reference should be had to the claims 35 which follow for a determination of the protection sought by this application.

I claim:

1. A machine for continuously unrolling a flat wide ribbon of waxed paper from a supply roll 40 on which it is wound, and folding and creasing it into a narrow folded and creased ribbon comprising means for holding a supply roll of flat wide ribbon in a condition where the wide ribbon can be unrolled readily therefrom, an elongated 45 stationary form having a head end adjacent the supply roll holding means, and a creasing means having a narrow slot through which may be passed the folded ribbon for creasing and disposed adjacent the tail end of the form, the supply roll holding means being so arranged with respect to the mouth of the creasing means slot that each half of the ribbon turns over a quarter turn on its way from the supply roll to the creasing means slot, the surface of the form at the 50 head end having each half a quarter turn removed from the positions of such surfaces at the tail end, the form having its convex surface coated with a rough yielding coating such as loose-woven felt, cloth, canvas, soft rubber, fiber, etc.

2. A machine for continuously unrolling a flat wide ribbon of waxed paper from a supply roll on which it is wound, and folding and creasing it into a narrow folded and creased ribbon comprising means for holding a supply roll of flat wide ribbon in a condition where the wide ribbon can be unrolled readily therefrom, an elongated stationary form having a head end adjacent the supply roll holding means, and a creasing means 55 having a narrow slot through which may be passed the folded ribbon for creasing and disposed adjacent the tail end of the form, the supply roll holding means being so arranged with respect to the mouth of the creasing means slot that each half of the ribbon turns over a quarter turn on its way from the supply roll to the creasing means slot, the surface of the form at the head end having each half a quarter turn removed from the positions of such surfaces at the tail end, the form having its convex surface 60 coated with a rough yielding coating such as loose-woven felt, cloth, canvas, soft rubber, fiber, etc.

so as to present a surface over which the ribbon can pass from the supply roll to the creasing means, the cross section of the form varying gradually from being substantially flat near the head end to a double fold U near the tail end, the form having its convex surface coated with a rough yielding coating such as loose-woven felt, cloth, canvas, soft rubber, fiber, etc.

3. A machine for continuously unrolling a flat wide ribbon of waxed paper from a supply roll 10 on which it is wound, and folding and creasing it into a narrow folded and creased ribbon comprising means for holding a supply roll of flat wide ribbon in a condition where the wide ribbon can be unrolled readily therefrom, an elongated 15 stationary form having a head end adjacent the supply roll holding means, and a creasing means having a narrow slot through which may be passed the folded ribbon for creasing and disposed adjacent the tail end of the form, the latter being of convex cross section throughout substantially its entire effective length and having its outer convex surface free of obstructions so as to present a surface over which the ribbon 20 can pass from the supply roll to the creasing means, the form having its convex surface coated with a rough yielding coating such as loose-woven felt, cloth, canvas, soft rubber, fiber, etc.

4. A machine for continuously unrolling a flat 30 wide ribbon of waxed paper from a supply roll on which it is wound, and folding and creasing it into a narrow folded and creased ribbon comprising means for holding a supply roll of flat wide ribbon in a condition where the wide ribbon can be 35 unrolled readily therefrom, an elongated stationary form having a head end adjacent the supply roll holding means, and a creasing means having a narrow slot through which may be passed the folded ribbon for creasing and disposed adjacent the tail end of the form, the latter being of convex cross section throughout substantially its entire effective length and having its outer convex surface free of obstructions so as to present a surface over which the ribbon 40 can pass from the supply roll to the creasing means, the form having its convex surface coated with a rough yielding coating such as loose-woven felt, cloth, canvas, soft rubber, fiber, etc.

the machine having a small resiliently mounted 50

and soft faced roll riding on the waxed paper as it passes continuously over the convex surface of the form.

5. A machine for continuously unrolling a flat wide ribbon of waxed paper from a supply roll 55 on which it is wound, and folding and creasing it into a narrow folded and creased ribbon comprising means for holding a supply roll of flat wide ribbon in a condition where the wide ribbon can be unrolled readily therefrom, an elongated stationary form having a head end adjacent the supply roll holding means, and a creasing means having a narrow slot through which may be passed the folded ribbon for creasing and disposed adjacent the tail end of the form, the supply roll holding means being so arranged with respect to the mouth of the creasing means slot that each half of the ribbon turns over a quarter turn on its way from the supply roll to the creasing means slot, the surface of the form at the head end having each half a quarter turn removed from the positions of such surfaces at the tail end, the form having its convex surface 60 coated with a rough yielding coating such as loose-woven felt, cloth, canvas, soft rubber, fiber, etc.

6. A machine for continuously unrolling a flat wide ribbon of waxed paper from a supply roll 65 on which it is wound, and folding and creasing it into a narrow folded and creased ribbon comprising means for holding a supply roll of flat wide ribbon in a condition where the wide ribbon can be unrolled readily therefrom, an elongated stationary form having a head end adjacent the supply roll holding means, and a creasing means having a narrow slot through which may be passed the folded ribbon for creasing and disposed adjacent the tail end of the form, the supply roll holding means being so arranged with respect to the mouth of the creasing means slot that each half of the ribbon turns over a quarter turn on its way from the supply roll to the creasing means slot, the surface of the form at the head end having each half a quarter turn removed from the positions of such surfaces at the tail end, the form having its convex surface 70 coated with a rough yielding coating such as loose-woven felt, cloth, canvas, soft rubber, fiber, etc.

7. A machine for continuously unrolling a flat wide ribbon of waxed paper from a supply roll 75 on which it is wound, and folding and creasing it into a narrow folded and creased ribbon comprising means for holding a supply roll of flat wide ribbon in a condition where the wide ribbon can be unrolled readily therefrom, an elongated stationary form having a head end adjacent the supply roll holding means, and a creasing means having a narrow slot through which may be passed the folded ribbon for creasing and disposed adjacent the tail end of the form, the supply roll holding means being so arranged with respect to the mouth of the creasing means slot that each half of the ribbon turns over a quarter turn on its way from the supply roll to the creasing means slot, the surface of the form at the head end having each half a quarter turn removed from the positions of such surfaces at the tail end, the form having its convex surface 80 coated with a rough yielding coating such as loose-woven felt, cloth, canvas, soft rubber, fiber, etc.

8. A machine for continuously unrolling a flat wide ribbon of waxed paper from a supply roll 85 on which it is wound, and folding and creasing it into a narrow folded and creased ribbon comprising means for holding a supply roll of flat wide ribbon in a condition where the wide ribbon can be unrolled readily therefrom, an elongated stationary form having a head end adjacent the supply roll holding means, and a creasing means having a narrow slot through which may be passed the folded ribbon for creasing and disposed adjacent the tail end of the form, the supply roll holding means being so arranged with respect to the mouth of the creasing means slot that each half of the ribbon turns over a quarter turn on its way from the supply roll to the creasing means slot, the surface of the form at the head end having each half a quarter turn removed from the positions of such surfaces at the tail end, the form having its convex surface 90 coated with a rough yielding coating such as loose-woven felt, cloth, canvas, soft rubber, fiber, etc.

9. A machine for continuously unrolling a flat wide ribbon of waxed paper from a supply roll 95 on which it is wound, and folding and creasing it into a narrow folded and creased ribbon comprising means for holding a supply roll of flat wide ribbon in a condition where the wide ribbon can be unrolled readily therefrom, an elongated stationary form having a head end adjacent the supply roll holding means, and a creasing means having a narrow slot through which may be passed the folded ribbon for creasing and disposed adjacent the tail end of the form, the supply roll holding means being so arranged with respect to the mouth of the creasing means slot that each half of the ribbon turns over a quarter turn on its way from the supply roll to the creasing means slot, the surface of the form at the head end having each half a quarter turn removed from the positions of such surfaces at the tail end, the form having its convex surface 100 coated with a rough yielding coating such as loose-woven felt, cloth, canvas, soft rubber, fiber, etc.

loose-woven felt, cloth, canvas, soft rubber, fiber, etc., the machine having a small resiliently mounted and soft faced roll riding on the waxed paper as it passes continuously over the convex 5 surface of the form.

6. A machine for continuously unrolling a flat wide ribbon of waxed paper from a supply roll on which it is wound, and folding and creasing it into a narrow folded and creased ribbon comprising means for holding a supply roll of flat wide ribbon in a condition where the wide ribbon can be unrolled readily therefrom, an elongated stationary form having a head end adjacent the supply roll holding means, and a creasing means having a narrow slot through which may be passed the folded ribbon for creasing and disposed adjacent the tail end of the form, the latter being of convex cross section throughout substantially its entire effective length and having its outer convex surface free of obstructions so as to present a surface over which the ribbon can pass from the supply roll to the creasing means, the cross section of the form varying gradually from being substantially flat near the head end to a double fold U near the tail end, the form having its convex surface coated with a rough yielding coating such as loose-woven felt, cloth, canvas, soft rubber, fiber, etc., the machine 20 having a small resiliently mounted and soft faced roll riding on the waxed paper as it passes continuously over the convex surface of the form.

7. A machine for continuously unrolling a flat wide ribbon of waxed paper from a supply roll 35 on which it is wound, and folding and creasing it into a narrow double folded and double creased ribbon comprising means for holding a supply roll of flat wide ribbon in a condition where the wide ribbon can be unrolled readily therefrom, an elongated stationary form having a head end adjacent the supply roll holding means, and a creasing means for deflecting the edges of the ribbon, as it passes along the form, against the form, and a slitting means for slitting the ribbon between 40 the creases thereof into two separate and independent narrow single folded and single creased ribbons.

8. A machine for continuously unrolling a flat wide ribbon of waxed paper from a supply roll on which it is wound, and folding and creasing it 50 into a narrow double folded and double creased ribbon comprising means for holding a supply roll of flat wide ribbon in a condition where the wide ribbon can be unrolled readily therefrom, an elongated stationary form having a head end adjacent the supply roll holding means, and a creasing means for deflecting the edges of the ribbon, as it passes along the form, against the form, the creasing means, ribbon, and form being so ar- 55

ranged that the edges of the ribbon do not overlap or meet but are transversely spaced from each other very slightly, after the creasing, by a fine longitudinal continuous space, and a slitting means for slitting the ribbon, at the space, into 5 two separate and independent narrow single folded and single creased ribbons.

9. A machine for continuously unrolling a flat wide ribbon of waxed paper from a supply roll on which it is wound, and folding and creasing it 10 into a narrow double folded and double creased ribbon comprising means for holding a supply roll of flat wide ribbon in a condition where the wide ribbon can be unrolled readily therefrom, an elongated stationary form having a head end 15 adjacent the supply roll holding means, and a creasing means for deflecting the edges of the ribbon, as it passes along the form, against the form, the creasing means, ribbon, and form being so arranged that the edges of the ribbon do not 20 overlap or meet but are transversely spaced from each other very slightly, after the creasing, by a fine longitudinal continuous space which is exactly midway between the creases of the ribbon, and a slitting means for slitting the ribbon, at the 25 space, into two separate and independent narrow single folded and single creased ribbons which are of exactly the same transverse width.

10. A machine for continuously unrolling a flat wide ribbon of waxed paper from a supply roll 30 on which it is wound, and folding and creasing it into a narrow double folded and double creased ribbon comprising means for holding a supply roll of flat wide ribbon in a condition where the wide ribbon can be unrolled readily therefrom, an elongated stationary form having a head end 35 adjacent the supply roll holding means, and a creasing means for deflecting the edges of the ribbon, as it passes along the form, against the form, and a slitting means for slitting the ribbon between the adjacent edges thereof into two separate and 40 independent narrow single folded and single creased ribbons.

11. A machine for continuously unrolling a flat wide ribbon of waxed paper from a supply roll 45 on which it is wound, and folding and creasing it into a narrow double folded and double creased ribbon comprising means for holding a supply roll of flat wide ribbon in a condition where the wide ribbon can be unrolled readily therefrom, an 50 elongated stationary form having a head end adjacent the supply roll holding means, and a creasing means for deflecting the edges of the ribbon, as it passes along the form, against the form, and a slitting means for slitting the ribbon along 55 a line close to and parallel to the adjacent edges thereof into two separate and independent narrow single folded and single creased ribbons.

FRANK M. HITNER.
